(57) CLAIM

The ornamental design for an earring, as shown and described.

DESCRIPTION

FIG. 1 is a perspective view of the earring showing my new design.

FIG. 2 is a front view thereof.

FIG. 3 is a back view thereof.

FIG. 4 is a left view thereof.

FIG. 5 is a right view thereof.

FIG. 6 is a top view thereof; and,

FIG. 7 is a bottom view thereof.

The broken lines shown in the drawings represent portions of the earring which form no part of the claimed design.
